W. CARPENTER.

LUBRICATOR.

APPLICATION FILED SEPT. 4, 1915.

1,186,279.

Patented June 6, 1916.

UNITED STATES PATENT OFFICE.

WILLIAM CARPENTER, OF LIBERTY, MISSOURI.

LUBRICATOR.

1,186,279.

Specification of Letters Patent.

Patented June 6, 1916.

Application filed September 4, 1915. Serial No. 48,993.

To all whom it may concern:

Be it known that I, WILLIAM CARPENTER, a citizen of the United States, and a resident of Liberty, in the county of Clay and State 5 of Missouri, have invented a new and Improved Lubricator, of which the following is a full, clear, and exact description.

My invention relates to lubricators of the kind in which a lubricant is atomized, sprayed, or otherwise finely divided and mixed with steam or other elastic fluid and by aid thereof introduced into other machinery, such, for instance, as the cylinders used upon locomotives and all other steam 10 motors.

More particularly stated, I seek to produce a lubricator of this general type in which the parts are all grouped together in practically a single body having a comparatively 15 simple construction as a whole.

My lubricator is economical in its action and has its various parts so arranged as to permit accessibility thereto.

My invention further contemplates various improvements in lubricators for the purpose of increasing the efficiency thereof.

Reference is made to the accompanying drawing forming a part of this specification, and in which like reference characters 25 indicate like parts, the figure showing partly in section and partly in elevation, the mechanism of my lubricator complete and parts immediately associated therewith.

The main steam pipe is shown at 1, and 30 extending laterally from it is a branch pipe 2 provided with a hand valve 3. A heating pipe 4 is provided with two hand valves 5, 5^a, and extends from the main steam pipe 1 to a T 6 with which the branch steam pipe 40 2 is provided. The branch steam pipe 2 leads to a condensing chamber 7, which, in this instance, is square in cross section. Connected with the condensing chamber and extending downwardly therefrom, is a pipe 8 45 for collecting and removing water of condensation. The pipe 8 is provided with a horizontally-extending portion 9 and with an upwardly-extending portion 10. A hand valve 12 is connected with the portions 9 and 10 just mentioned. Another hand valve 50 11 controls communication between the portion 9 of the pipe and the main body thereof extending to the condensing chamber 7. The portion 10 of the pipe is connected to the bottom of an oil chamber 13. Located within 55 this oil chamber is an oil pipe 14, the

upper end of which determines the level 15 of a quantity of oil contained within the oil chamber. A hand valve is shown at 16, and is provided with a controlling wheel 18. A hand valve 17 is used for discharging water. Extending upwardly from the valve 16 is a transparent tube 19, and extending into the lower end of this tube is a needle 19^a through which the lubricant may be discharged in 60 small quantities. The tube 19 and parts associated therewith together constitute a sight feed for the lubricant.

Connected with the upper end of the tube 19 is a delivery pipe 20, which extends across 65 the oil chamber and is inclined slightly. The delivery pipe 20 terminates in a spout 21, which is located within a baffle chamber 22. Disposed within this baffle chamber are baffle plates 23, 24, 25, staggered relatively to each 70 other and each inclined in order to facilitate drainage from it. The bottom 26 of the baffle chamber is also inclined. A pipe 27 leads from the baffle chamber 22 to the main steam pipe 1, and is provided with a hand 75 valve 28. The pipe 27 is provided with a nozzle 29, which extends into the main steam pipe and carries an oil spoon 30. The upper end of the oil chamber 13 is provided with a slanting floor 31 and with a flaring wall 80 32, so as to form a pocket. A closure plug 33 controls communication between this pocket and the inside of the oil chamber 13.

The oil pipe 14 extends to a sufficient height within the oil chamber 13 to prevent 85 the entrance of sediment from the oil chamber into the oil pipe. The level of oil within the oil chamber may be as indicated at 15, or at any higher level. The oil chamber 13 and the baffle chamber 22, that is to say, the 90 atomizing chamber, are here conveniently made in one casting.

As shown the casting is in the form of a casing having a vertical partition dividing 95 it into the two chambers. The baffle chamber terminates short of the lower end of the oil chamber, and it is also of less diameter than the oil chamber, so that it is considerably smaller than the oil chamber. By thus constructing the oil and baffle chambers, the 100 heat of the baffle chamber assists in heating the oil of the oil chamber.

The operation of my device is as follows: The parts being assembled and arranged as 105 above described and as shown in the drawing 110 steam from the main steam pipe 1 passes into the branch steam pipe 2, and thence

through the pipe 32 into the baffle chamber 22. A portion of the steam from the pipe 2 passes into the upper end of the pipe 4, and another portion passes into the condensing chamber 7. Any water of condensation collected within this chamber drips downwardly through the pipe 8 and may be discharged at intervals by aid of the hand valve 12. By turning the hand valve 5^a, fresh live steam from the main steam pipe may be admitted into the pipe 4, so as to heat the oil chamber 13. By adjusting the hand valves 5 and 5^a, steam may be admitted at both ends of the pipe 4, or at either end thereof. In other words, the proportion of fresh live steam directly from the steam pipe 1 as compared with steam from the branch steam pipe 2, may be regulated at the will of the operator.

Oil is introduced into the oil chamber 13 by removing the closure plug 33, and pouring the oil into the pocket formed by the slanting floor 31 and the flaring wall 32. The oil within the upper portion of the oil chamber 13 now finds its way into the oil pipe 14, whereby it is carried into the valve 16 and thence makes its escape upwardly through the tube 19, which with adjacent parts constitutes a sight feed as above explained. The oil rises through the sight feed and is delivered one drop at a time into the adjacent end of the pipe 20. The oil flows along this pipe and drips off within the baffle chamber 22, striking the baffle plates 23, 24, 25, and the slanting bottom 26 in succession. The hand valve 28 being open, live steam from the main steam pipe 1 can readily pass through the pipe 27 into the baffle chamber 22. Steam can also pass from the branch steam pipe 2 downwardly through the pipe 32 into the baffle chamber. Hence, the oil dripping upon the baffle plates 23, 24, 25 and slanting bottom 26 of the baffle chamber, is subjected to the direct action of the hot steam, and that too under conditions which facilitate the atomizing of the oil. The result is a mixture of finely divided oil and steam, and this mixture passes through the pipe 27, valve 28 and nozzle 29, into the main steam pipe 1. The oil spoon 30 catches and retains any oil which may be delivered

into the main steam pipe 1 without being completely atomized, and the hot steam in the main steam pipe soon reduces this oil from its liquid form to a finely divided or comminuted form, that is, such oil as collects in the spoon 30 is readily atomized.

I do not limit myself to the precise construction shown as variations may be made therefrom without departing from the spirit of my invention.

Having thus described my invention, what I claim as new and desire to secure by Letters Patent is:

1. In a lubricator, a casing divided by a vertical partition into an oil chamber and a baffle chamber, the baffle chamber being smaller than the oil chamber and provided with baffle plates, pipes leading from opposite ends of the baffle chamber and adapted to be connected with a steam pipe, a sight feed connected with the oil chamber, and an oil pipe leading from the sight feed through the oil chamber into the baffle chamber.

2. In a lubricator, a casing divided by a partition into an oil chamber and a baffle chamber, the baffle chamber being smaller than the oil chamber and provided with inclined and staggered baffle plates, pipes leading from opposite ends of the baffle chamber and adapted to be connected with a steam pipe, a pipe extending through the oil chamber and adapted to have its ends connected with a steam pipe, a sight feed at the side of the oil chamber opposite the baffle chamber and connected with the oil chamber, and an oil pipe leading from the sight feed through the oil chamber into the baffle chamber.

3. In a lubricator, the combination of a steam pipe, means for atomizing oil to be introduced into said steam pipe, and a branch pipe extending into said steam pipe for discharging said oil thereinto, the end of said branch pipe located within said steam pipe being formed into a spoon for holding liquid oil within said steam pipe.

WILLIAM CARPENTER.
